(57) **CLAIM**

The ornamental design for a bottle, as shown and described.

DESCRIPTION

FIG. 1 is a perspective view of a first embodiment of a bottle according to our new and ornamental design;

FIG. 2 is a front elevation view thereof;

FIG. 3 is a rear elevation view thereof;

FIG. 4 is a right side elevation view thereof, wherein the left side elevation view thereof is a mirror image;

FIG. 5 is a top plan view thereof; and

FIG. 6 is a bottom plan view thereof.

FIG. 7 is a perspective view of a second embodiment of a bottle according to our new and ornamental design;

FIG. 8 is a front elevation view thereof;

FIG. 9 is a rear elevation view thereof;

FIG. 10 is a right side elevation view thereof, wherein the left side elevation view thereof is a mirror image;

FIG. 11 is a top plan view thereof; and,

FIG. 12 is a bottom plan view thereof.

The dash-dot broken lines show the boundaries of the claimed design and form no part of the claim. The evenly dashed broken lines show portions of the bottle that form no part of the claim.

1 Claim, 10 Drawing Sheets
